United States Patent Office

Des. 230,578
Patented Mar. 5, 1974

230,578

TRAILER

Harry L. Taylor, Merriam, Kans., assignor to Taylor
Industries, Inc., Merriam, Kans.

Filed Jan. 10, 1972, Ser. No. 216,918

Term of patent 14 years

Int. Cl. D12—10

U.S. Cl. D12—103

Fig. 1.

Fig. 2.

Fig. 3.

Fig. 4.

Fig. 5.

Fig. 6.

FIG. 1 is a front perspective view of the trailer, showing my new design;

FIG. 2 is a left side elevational view thereof, with the front portion of the trailer hitch being omitted for ease of illustration;

FIG. 3 is a top plan view thereof;

FIG. 4 is a right side elevational view thereof;

FIG. 5 is a front elevational view thereof; and

FIG. 6 is a rear elevational view thereof.

I claim:

The ornamental design for a trailer, as shown and described.
